US00D896958S

(12) **United States Design Patent** (10) Patent No.: **US D896,958 S**
(45) Date of Patent: **** Sep. 22, 2020**

(54) **INTRAVAGINAL DEVICE**

(71) Applicant: **Renovia Inc.**, Boston, MA (US)

(72) Inventors: **Marc D. Beer**, Sudbury, MA (US);
Jose Bohorquez, Boston, MA (US);
Samantha J. Pulliam, Boston, MA (US);
Jessica L. McKinney, Boston, MA (US)

(73) Assignee: **Renovia Inc.**, Boston, MA (US)

(**) Term: **15 Years**

(21) Appl. No.: **29/687,209**

(22) Filed: **Apr. 11, 2019**

(51) LOC (12) Cl. **24-02**

(52) U.S. Cl.

USPC **D24/141**

(58) **Field of Classification Search**

USPC D24/135, 140–141; 128/884–885;
600/29–30

CPC A61F 2/005; A61F 2/0027; A61F 2/0031;
A61F 2/0009; A61F 2/0036; A61F 2/0045

See application file for complete search history.

(57) **CLAIM**

The ornamental design for an intravaginal device, substantially as shown and described.

DESCRIPTION

FIG. 1 is a front and left side perspective view of an intravaginal device embodying the claimed design.

FIG. 2 is a front view of the intravaginal device of FIG. 1.

FIG. 3 is a rear view of the intravaginal device of FIG. 1.

FIG. 4 is a right side view of the intravaginal device of FIG. 1.

FIG. 5 is a left side view of the intravaginal device of FIG. 1.

FIG. 6 is a top view of the intravaginal device of FIG. 1; and, FIG. 7 is a bottom view of the intravaginal device of FIG. 1.

1 Claim, 7 Drawing Sheets
